UNITED STATES PATENT OFFICE.

FERDINAND BURCHARTZ, OF NEW YORK, N. Y.

CONSTRUCTION OF BUILDINGS.

1,149,180.

Specification of Letters Patent. Patented Aug. 10, 1915.

Application filed January 12, 1911. Serial No. 602,296.

To all whom it may concern:

Be it known that I, FERDINAND BURCHARTZ, a citizen of the United States, and resident of the borough of Manhattan, city, 5 county, and State of New York, have invented certain new and useful Improvements in the Construction of Buildings, of which the following is a specification.

My present invention relates to the construction of buildings and particularly to 10 floors and ceilings comprising blocks and reinforcing wires, and has for its object to provide a simple, strong and inexpensive construction of the character indicated 15 above.

In Letters Patent of the United States No. 875318, granted to me on December 31, 1907, I have disclosed a building block made of 20 two sections having open sides and set together so that the open sides meet, the joined sections thus forming a block having closed walls.

My present invention relates to a particular way of arranging sectional blocks in a 25 floor or the like, the joints extending in different directions in the several blocks, thus securing a stronger construction.

Reference is to be had to the accompanying drawings, in which—

30 Figure 1 is a plan of an unfinished floor containing blocks laid according to my invention; Fig. 2 is a perspective view showing two block sections, with open ends, as they come from the press; Fig. 3 is a vertical section of one of these sections, placed on a suitable support for the purpose of closing one end by a layer of cement or the like; Fig. 4 is a perspective view of the block section resulting from the treatment illustrated by Fig. 3.

I first make hollow block sections of uniform cross section such as can be produced by pressing concrete or other suitable plastic material through a die and cutting the 45 resulting tube or bar at regular intervals, in a manner now well-known in the art. One form of block sections of this character is shown in Fig. 2, where each of the two sections has the shape of a rectangular tube, open at both ends, and provided with a top wall A, a bottom wall B, side walls C, and longitudinal flanges B' forming extensions of the bottom wall B along the outside of the side walls C. Having produced such hollow block sec-

tions open at both ends, I place them with 55 one of the open ends on a suitable smooth supporting surface, such as a horizontal wooden board D (see Fig. 3), and with a trowel or other convenient tool I fill into the cavity of the block section, a sufficient 60 amount of cement or other suitable plastic adhesive material to form a continuous layer E at the bottom of said cavity, flush with the edges of the top A, of the bottom B and of the side walls C which are in engagement 65 with the support D. No particular care is required in applying this layer E, since its bottom surface will become smooth by contact with the board D, while its top surface or inner surface may be quite uneven or 70 rough, as shown in Fig. 3. Preferably the filling E is made of the same composition as the body of the block, or of a similar composition, in which case the joints at the edges of the filling will be invisible, so that 75 its outer surface will appear to be continuous with the edges of the walls A, B, C, and of the flanges B', as shown in Fig. 4. The block sections thus obtained are closed at one end and open at the opposite end. They 80 may be utilized in various ways for constructing walls, floors, or ceilings of buildings. I prefer to set two such sections together with their open ends in contact, thus forming hollow square blocks whose walls 85 are imperforate, that is to say, the cavity within such blocks is closed entirely. In Fig. 1, a series of such blocks are shown, the letter a indicating the joints formed by the abutting open ends of two block sections. 90 In order that two sections may form together a square block, as shown, each of the sections should have the shape of a rectangle one side of which is twice as long as the other. The blocks are then laid in the 95 manner shown in Fig. 1, with the joints a being placed alternately (in each row and in each column) in two positions one at a right angle to the other. The flanges B' of each block abut against the closed end wall 100 E of an adjacent block and form channels running at right angles between the rows of blocks, the bottoms of these channels being closed by said flanges between the sides of the blocks and open between the corners 105 thereof. The customary reinforcing rods F and F' are then placed in said channels or grooves above the flanges B', and the floor

is completed in the usual manner by filling the voids with cement or the like (not shown) in which said rods become embedded. The cement fills the open corner spaces between the flanges of the blocks.

The floor thus laid comprising rectangular blocks spaced apart and disposed in checkerboard fashion with the reinforced cement fillings in the channels running at right angles between the blocks, constitutes a strong substantial and durable floor.

Various modifications may be made without departing from the nature of my invention as set forth in the appended claims.

15 I claim:

1. A floor or the like comprising rectangular blocks spaced apart and disposed in checkerboard fashion, said blocks having respectively two opposite flanged sides and being disposed with the flanges of alternative blocks running at right angles to the flanges of intermediate blocks, the flanges of one block abutting the plain sides of adjacent blocks and forming channels running at right angles between the rows of blocks, the bottoms of said channels being closed by said flanges between the sides of the blocks and open between the corners thereof, reinforcing rods disposed in said channels and crossing one another at said open corners,

and cement fillings in said channels and open corners and surrounding said rods.

2. A floor or the like comprising rectangular blocks spaced apart and disposed in checkerboard fashion, said blocks being composed of hollow sections assembled in pairs and open at their meeting ends, said blocks having respectively two opposite plain sides and two opposite flanged sides and being disposed with the flanges of alternative blocks running at right angles to the flanges of intermediate blocks, the flanges of one block abutting the plain sides of adjacent blocks and forming channels running at right angles between the rows of blocks, 45 the bottoms of said channels being closed by said flanges between the sides of the blocks and open between the corners thereof, reinforcing rods disposed in said channels and crossing one another at said open corners, and cement fillings in said channels and open corners and surrounding said rods.

In testimony whereof, I have signed this specification in the presence of two subscribing witnesses.

FERDINAND BURCHARTZ.
